UNITED STATES PATENT OFFICE.

EDWARD F. WILSON, OF WEBSTER GROVES, MISSOURI.

CARD INDEX AND DISPLAY DEVICE.

1,336,115.

Specification of Letters Patent.

Patented Apr. 6, 1920.

Application filed June 17, 1918. Serial No. 240,414.

To all whom it may concern:

Be it known that I, EDWARD F. WILSON, a citizen of the United States, residing at Webster Groves, St. Louis county, Missouri, 5 have invented a new and useful Card-Index and Display Device, of which the following is a specification.

This invention relates to card index and display devices.

10 An object of the invention is to provide a novel support comprising a frame composed of paper or other appropriate material having a flexible connection with a retaining element and having means for supporting a 15 card or piece of paper containing records, data, information, or pictures on both sides, said frame being open and having a window through which one of the sides of the card or piece of paper supported thereby is 20 displayed, thus rendering the contents of both sides of the card or piece of paper plainly visible.

Other objects will appear from the following description in which reference is 25 made to the accompanying drawings, in which—

Figure 1 is a view illustrating a series of the indexes and display devices supported in frames.

30 Fig. 2 is an end elevation or view showing the cards or pieces of paper containing the records connected with the supporting display frames.

Fig. 3 is a view of one of the card supporting frames without any card being connected therewith.

35 Fig. 4 is a view of the opposite side of the frame, the display card in connection therewith being broken to illustrate the 40 means by which the display card is supported in connection with the frame.

Figs. 5 and 6 are views showing the opposite sides of a card which has been used with satisfactory results.

45 Numbers of the supporting frames may be assembled together and conveniently arranged in frames in any desired arrangement whether alphabetical or otherwise. As shown in Fig. 1 numerous card supports 50 are arranged in a frame 1 having a flexible connection with a matching frame 2 in

which other card supports are similarly arranged. The frames 1 and 2 may be folded together like the covers of a book to inclose or confine the card supports between them, 55 it being understood that the card supports of each series lie flat against each other so that relatively a small amount of space is occupied by a considerable number of the card supports.

As will be understood by reference to Figs. 3 and 4, the specific form of the invention shown comprises a frame which may be composed of paper or other appropriate material, said frame being provided with a 60 section 3 of cloth secured to one edge thereof and also secured to a strip 4 of wood, metal or other appropriate material which has its ends extending beyond the ends of the frame and adapted to engage under the 65 flanges 5 in the frames 1 and 2. The cloth connecting each frame with its supporting member 4 is a strip of cloth of equal length with the frame, having one side edge secured to one side of the frame, and the 70 member 4 secured to the same side of the cloth strip a slight distance away from and parallel with the edge of the frame. This permits each frame to be folded from one position to another as will be readily 75 understood by reference to Fig. 2. The engagement thus made between the strips 4 and the frames in which they are mounted permits the strips and the frames supported thereby to be readily removed. The sections 80 of cloth constituting the connection between the card supporting frames and the strips 4 are flexible so that the card supporting frames may be readily turned over in the frames 1 and 2 like the leaves of a 85 book.

90 Each of the card supporting frames in the form illustrated includes a portion 6 to which the cloth 3 is secured; parallel portions 7 extending from the ends of the portion 6; and a connection 8 between the ends of the extensions 7 composed preferably of some transparent material such, for instance, as mica, transparent paper or the like. The connection 8 is secured to the extensions 7 by fasteners 9 and is folded around on both sides of the extensions 7 so

that one edge of the card when placed in the supporting frame may be inserted between the folds of the connection 8 and thereby retained in position in the frame.

5 The frame is formed with a pair of angular cuts 10 arranged to receive the corners of the card and may also be provided intermediate of the cuts 10 with a tongue 11 adapted to engage over the edge of the card 10 to retain the intermediate portion thereof against the frame.

As illustrated in Figs. 5 and 6 the card is intended to have on both sides thereof appropriate data or information in the form 15 of writing, drawings or photographs, and on the marginal edge thereof, which is embraced between the folds of the connection 8, an appropriate index is intended to be printed or written as shown in Fig. 4. In 20 Figs. 5 and 6 are shown opposite sides of a card, one side of which may contain a photograph or other pictorial matter, together with an index, and the opposite side of which may contain descriptive matter together with an index. The indexes thus arranged are visible on all of the cards when they are mounted in their supporting frame or book. Visibility of the indexes when the cards are arranged in book form is made 25 possible by the fact that the strips 4 are of sufficient width to hold the card supporting frames in stepped positions. This holds a portion of the marginal edge of each card in plain view of the user, irrespective of the 30 direction in which the cards lie.

35 By this improved construction I am enabled to obtain full use of both sides of the card. For instance, I have employed the invention as an index and card display system in the real estate business. As employed, I have had on one side of each card a photograph of the building or piece of real estate listed and on the opposite side of the card I have had printed, stamped or written appropriate information concerning the building 40 or piece of real estate shown by the photograph on the opposite side of the card. The invention thus used has been highly satisfactory and is a much greater convenience 45 and advantage than anything heretofore devised for the same purpose. It will be apparent, however, that the advantage and utility of the device is not restricted to the real estate business but that it may be used 50 with equal advantage in other lines of business.

55 What I claim and desire to secure by Letters Patent, is:—

1. A device of the character described, 60 comprising a frame having an opening through the center thereof, constituting a window for exposing to view one side of a card, and a folded section of transparent material at one side of the frame, and elements fastening said material to the frame;

a supporting element parallel with the side edge of the frame opposite from the transparent material; a flexible connection securing the frame to said supporting element and permitting said frame to be turned over 70 from one side to the other; and means on the frame adjacent to said support to prevent lateral and endwise movement of the card while the other edge of the card is between the folds of said transparent material in position so that the contents of one side of the card are visible through the opening and the contents of the other side of the card are visible when the frame is turned over.

2. A device of the character described, 80 comprising a supporting frame; a series of card-carrying frames mounted in the supporting frame and arranged to be turned to present to view the opposite sides thereof, each of said supporting frames having a central opening for displaying the contents of one side of the card carried thereby; a transparent member for supporting a card in each of said frames in position to display the contents of one side thereof, in part through 85 said transparent member, and to display the contents of the opposite side thereof through said opening when the card-carrying frame is turned over; means for engaging the card in each frame adjacent to the edge opposite 90 from said member to prevent longitudinal or lateral movement of the card; a supporting element for each card frame mounted in said supporting frame; and a flexible connection between each card frame and the correspond- 95 ing supporting element.

3. A device of the character described, comprising a frame, one side of said frame being composed of a transparent material folded to provide two side portions adapted 105 to receive between them the marginal edge of a card; means adjacent the edge of the card opposite that which is placed between said transparent side portions for engaging and holding said card from endwise and 110 lateral movement; and a supporting element connected to the side edge of said frame adjacent to which said engaging means is located.

4. A device of the character described, 115 comprising a frame one side of which is composed of transparent material folded to provide two side portions adapted to receive between them the marginal edge of a card containing written or printed matter on both 120 sides thereof which may be viewed through said transparent material while the card is in position; and means on the frame for engaging the opposite edge of the card to prevent lateral or longitudinal movement of 125 the card.

5. A device of the character described, comprising a frame one side of which is composed of transparent material folded to provide two side portions adapted to receive 130

between them the marginal edge of a card containing written or printed matter on both sides thereof which may be viewed through said transparent material while the card is in position; means on the frame for engaging the opposite edge of the card to prevent longitudinal and lateral movement of the

card; a supporting element; and a flexible connection between the frame and said supporting element permitting the frame to be turned to present to view either side of the card mounted in the frame.

EDWARD F. WILSON.
